PRESSURE HEAD BOX FOR PAPER MACHINES

William P. Shannon, Port St. Joe, Fla.

Application September 12, 1945, Serial No. 615,866

8 Claims. (Cl. 92—44)

1

This invention relates to a pressure head box for paper machines, and more particularly to such a head box adapted to be used with paper making machines of the Fourdrinier type.

A primary object of this invention is the provision of an improved headbox adapted to take the stock from a mixing pump at any given consistency and feed the same from the headbox to a Fourdrinier screen traveling at given speeds in the form of a web or mat with a uniformity 10 across the width of the screen.

An additional object of the invention is the provision of such a device provided with an adjustable lip and slice for regulating the thickness of the flow over the complete width of the screen.

Still another object of the invention is the provision of such a device adapted to feed the mix under pressure by the means of a power driven helix through a tortuous channel provided with baffles to insure a thorough mixing and uniform flow prior to the ejection of the mix onto the Fourdrinier screen.

A further object of the invention is the provision of such a pressure head provided with means whereby a relatively high pressure may be maintained therewithin, the pressure being uniform throughout the entire width of the head, and provided with a plurality of pressure gauges whereby the pressure at various predetermined points may be readily determined in conjunction with the speed that the Fourdrinier screen is traveling.

Still other objects reside in the provision of such a device which will be sturdy and durable in construction, reliable and efficient in operation, and relatively simple and inexpensive to manufacture, assemble and install, on any conventional paper machine of the Fourdrinier type.

Other objects reside in the combinations of elements, arrangements of parts, and features of construction, all as will be more fully pointed out hereinafter and disclosed in the accompanying drawings wherein there is shown a preferred embodiment of this inventive concept.

In the drawings:

Figure 1 is a side elevational view, certain parts thereof being broken away, disclosing one form of pressure head embodying the instant inventive concept.

Figure 2 is a top plan view of the device disclosed in Figure 1.

Figure 3 is a sectional view taken substantially along the line 3—3 of Figure 1 as viewed in the direction indicated by the arrows.

2

Figure 4 is a sectional view taken substantially along the line 4—4 of Figure 2 as viewed in the direction indicated by the arrows, and

Figure 5 is a sectional view taken substantially along the line 5—5 of Figure 1 as viewed in the direction indicated by the arrows.

Similar reference characters refer to similar parts throughout the several views of the drawings.

Having reference now to the drawings, and more particularly to Figure 1, there is generally indicated at 10 a mixing pump adapted to mix the stock preparation with water to obtain a desired consistency and pressure. From the mixing pump 10 a pressure tube 11 leads upwardly through a horizontal bend 12 up and thence vertically through a section 13 to a horizontal portion 14 provided with a gate valve 15, to a vertical portion 16 which enters, through a sealed inlet 17, into the end 18 of the pressure box, generally indicated at 19. Pressure gauges 20 and 21 are provided in the horizontal portions 12 and 14, respectively, on opposite sides of the gate valve 15.

The end 18 of the pressure box 19 is provided with an end cap 22 secured thereto by bolts, and has a centrally positioned aperture through which extends a shaft 23, a sealing gasket 24 being held in place by a threaded cap 25 to preclude passage of fluid outwardly along the shaft (see Figure 4). The end of the shaft 23 outwardly of the box 19 is provided with a pulley 26, driven by a belt 27 which, in turn, is driven by a pulley 28 mounted on the drive shaft 29 of a suitable electric motor 30 or similar source of power.

As best shown in Figure 4, the shaft 23 extends entirely through the pressure box 19 and is journaled as in a bearing 31 in a projecting portion 32 of the opposite end wall 33 of the box 19. A helix 34 extends about the shaft 23 within the box 19 for the purpose of feeding the mix from the inlet 17 longitudinally throughout the length of the box.

As best shown in Figure 5 the box 19 is provided in the base thereof with a longitudinally extending outlet 35 which communicates with a tubular member 36 surrounding the box 19 coaxially and provided interiorly with a plurality of longitudinally extending spaced baffles 37, erucate in cross section. The tubular chamber 36, in turn, communicates through an outlet 38 with a second tubular member 39 similarly provided with baffles 40 from which, in turn, an outlet 41 leads to a plate 56 of non-corrosive material commonly called an apron board adapted for

the purpose of keeping an even flow of the width of the screen or Fourdrinier wire for the bottom of the outlet.

A plate 42 constructed of non-corrosive material commonly called a deckle is provided for the purpose of keeping the flow of the mix off the edges of the screen or Fourdrinier wire.

A lip or slice 43 is pivotally secured as by pivot pins 44 to the outer tubular casing 39 adjacent and above the outlet 41. The pivots 44 are suitably journaled in projecting lugs 45 secured adjacent the extremities of the box.

As best shown in Figure 5 the outer extremities of the slice 43 are provided with upstanding lugs 46 to which are pivotally secured, as by pivots 47, the extremities of bolts 48 which pass through threaded apertures in protruding lugs 49 secured to the outer portion of tubular casing 39. Nuts 50 serve to control the relative position of the bolts with respect to the lugs 49 and hence vary the relative height of the opposite end of the slice 43. Additional bolts 51 pass through threaded apertures in lugs 52 secured at suitably spaced intervals to the outer wall of the tubular member 39 and the lower extremities of the screws 51 are adapted to bear against intermediate portions of the slice in such manner as to exert a uniform pressure thereon, which may be adjusted at the will of the operator. Obviously, the relative position of the slice as adjusted by means of the nuts 50 will determine the thickness of the mix fed over the deckle to the forming board.

As best shown in Figure 3, the forming board includes the customary breast roll 53 and a plurality of table rolls 54. The entire assembly may be supported on legs 55 of any desired height or configuration.

From the foregoing the operation of the device should now be readily understandable. A previously prepared mixed pulp including a requisite amount of water is passed from the mixing pump into the tubular passages 11, 12 and 13, at a greater pressure than is actually needed in order to regulate the pressure box properly. As more pulp under pressure is needed in the pressure box it is admitted through the medium of the gate valve 15 and passes through the inlet 17 into the box 19 being fed therealong by the helix 34. Obviously, the mixed pulp passes then through the outlet 35 into the tubular member 36 being agitated by the baffles 37 and thence through the outlet 38 into the tubular members 39 and therearound emerging from the outlet 41 under the slice 43 and thence to the forming board and into the paper machine to be processed in the conventional manner.

From the foregoing it will now be seen that there is herein provided a device accomplishing all the objects of this invention and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. A pressure head box for paper machines including a pressure chamber, a cylindrical pressure head tube, an inlet for paper mix through said pressure chamber, a cylindrical tube coaxial with said chamber, means including a longitudinally extending slot connecting said chamber and said tube, a second tube coaxial with said cylind-

rical first-mentioned cylindrical tube and having a longitudinal slot communicating therewith, an outlet for said last-mentioned tube comprising a longitudinal slot, and an adjustable slice adjacent said outlet.

2. A pressure head box for paper machines including a pressure chamber, a cylindrical pressure head tube, an inlet for paper mix through said pressure chamber, a cylindrical tube coaxial with said chamber, means including a longitudinally extending slot connecting said chamber and said cylindrical tube, a second tube coaxial with said first-mentioned cylindrical tube and having a longitudinal slot communicating therewith, an outlet for said last-mentioned tube comprising a longitudinal slot, a power driven feed helix in said box, and an adjustable slice adjacent said outlet.

3. A pressure head box for paper machines including a pressure chamber, a cylindrical pressure head tube, an inlet for paper mix through said pressure chamber, a cylindrical tube coaxial with said chamber, means including a longitudinally extending slot connecting said chamber and said cylindrical tube, a second tube coaxial with said first-mentioned cylindrical tube and having a longitudinal slot communicating therewith, an outlet for said last-mentioned tube, comprising a longitudinal slot, a power driven feed helix in said box, an adjustable slice adjacent said outlet, and arcuate mixing baffles in both of said tubes.

4. In a paper machine, a pressure head tube, a chamber extending transversely of said tube, means for supplying paper pulp to said chamber, a helical conduit co-axial with said chamber, means connecting said chamber with one end of said conduit and an adjustable slice connected with the other end of said conduit.

5. In a paper machine, a pressure head tube, a chamber extending transversely of said tube, means for supplying paper pulp to said chamber, a helical conduit co-axial with said chamber, means connecting said chamber with one end of said conduit and an adjustable slice connected with the other end of said conduit, said chamber having a power driven paper pulp feeding means therein.

6. In a paper machine, a pressure head tube, a chamber extending transversely of said tube, means for supplying paper pulp to said chamber, a helical conduit co-axial with said chamber, means connecting said chamber with one end of said conduit and an adjustable slice connected with the other end of said conduit, said chamber having a power driven paper pulp feeding means therein, said last means communicating with said conduit throughout the width thereof.

7. A pressure head device for a paper machine including a casing, a central chamber transverse said casing, means for feeding paper pulp axially into said chamber, a longitudinal discharge slot in said chamber, power operated pressure means for delivering paper pulp from said chamber through said discharge slot, a spiral fin surrounding said chamber between said chamber and casing and forming a spiral delivery conduit communicating with said discharge slot, a longitudinal slot forming a discharge orifice from said conduit and an adjustable slice controlling the delivery from said orifice.

8. A pressure head device for a paper machine including a casing, a central chamber transverse said casing, means for feeding paper pulp axially into said chamber, a longitudinal discharge slot in said chamber, power operated pressure means

for delivering paper pulp from said chamber through said discharge slot, a spiral fin surrounding said chamber between said chamber and casting and forming a spiral delivery conduit communicating with said discharge slot, a longitudinal slot forming a discharge orifice from said conduit and an adjustable slice controlling the delivery from said orifice, said fin having transversely extending mixing baffles on opposite sides thereof.
